UNITED STATES PATENT OFFICE.

ADOLPH ROSENBERG, OF CHICAGO, ILLINOIS.

CONDIMENT-HOLDER.

No. 890,304.

Specification of Letters Patent.

Patented June 9, 1908.

Application filed July 16, 1907. Serial No. 383,998.

To all whom it may concern:

Be it known that I, ADOLPH ROSENBERG, citizen of the United States, residing at Chicago, in the county of Cook and State of Illinois, have invented certain new and useful Improvements in Condiment-Holders, of which the following is a specification.

The present invention relates to improvements in condiment holders and more particularly to a combined salt and pepper shaker embodying novel means for closing either the salt compartment or the pepper compartment.

To this end the invention resides principally in the provision of a receptacle formed with a plurality of compartments, each of the compartments being provided with a perforated closure, and a swinging plate peculiarly mounted and formed so as to effectively close either set of perforations.

For a full description of the invention and the merits thereof and also to acquire a knowledge of the details of construction and the means for effecting the result, reference is to be had to the following description and accompanying drawings, in which:

Figure 1 is a perspective view of a salt and pepper shaker embodying the invention. Fig. 2 is a longitudinal sectional view 30 through the same. Fig. 3 is a top plan view. Fig. 4 is a detail view of the swinging closure.

Corresponding and like parts are referred to in the following description and indicated in all the views of the drawings by the same reference characters.

In the present instance the invention is shown as embodying a salt and pepper shaker comprising a receptacle 1 formed with a salt compartment 2 and a pepper compartment 3. The mouths of the two compartments 2 and 3 are located adjacent each other and are closed by a common cap 4. This cap comprises a pair of disks 5 connected by a neck 6, each of the disks 5 having the central portion thereof pressed outwardly as indicated at 7 and provided with the usual perforations 8. Extending around the cap 4 is a flange 9 designed to receive the mouth of the receptacle 1 in the usual manner, and 50 in the present instance spring tongues 10 are shown as cut from the flange 9 and having a spring engagement with the said receptacle.

A pair of spaced ears 11 project outwardly from the neck 6 and pivotally mounted between these ears 11 is an arm 12 projecting from a swinging plate 13 designed to be

swung over either set of the perforations 8. If found desirable as in the present instance this swinging plate may be provided with a finger-piece 14. An opening 15 is formed in the neck 6 between the spaced ears 11 and extending over the opening under the arm 12 is a spring strip 16 the ends of which engage the outwardly pressed portion 7 of the disks 5 whereby the spring is held against accidental displacement. The arm 12 extends slightly beyond the pivot point as indicated at 17 and this extension 17 co-operates with the spring strip 16 to hold the swinging plate 13 either extending outwardly so that both sets of the perforations 8 are uncovered or against either of the disks 5.

For the purpose of enabling the plate 13 to effectively close the perforations 8 the same is provided upon its opposite faces with 75 projections 18 corresponding to the perforations and designed to enter the same when the plate is swung against the corresponding disk.

Having thus described the invention, what 80 is claimed as new is:

1. A closure of the character described comprising a pair of perforated disks connected by a neck having an opening therein, ears projecting from the said neck upon opposite sides of the opening, a spring strip extending across the opening and located between the ears, and a swinging closure pivotally mounted between the ears and provided with an extension engaging the spring 90 which serves to hold the swinging closure against either of the disks.

2. A closure of the character described comprising a pair of perforated disks connected by a neck having an opening therein, 95 portions of the disks being pressed outwardly, a spring strip extending across the opening in the neck, the said strip being located between the spaced ears and the ends of the strip being adapted to engage the outwardly 100 pressed portions of the disks to hold the strip against displacement, and a swinging closure pivotally mounted between the ears and adapted to be held against either of the disks by means of the spring strip. 105

In testimony whereof I affix my signature in presence of two witnesses:

ADOLPH ROSENBERG. [L.S.]
